CAR-TRUCK.

No. 820,718.

Specification of Letters Patent.

Patented May 15, 1906.

Application filed June 17, 1905. Serial No. 265,742.

To all whom it may concern:

Be it known that I, PETER N. HYDEN, a citizen of the United States, residing at Chicago, county of Cook, State of Illinois, have 5 invented a certain new and useful Improvement in Car-Trucks; and I declare the following to be a full, clear, and exact description of the invention, such as will enable others skilled in the art to which it pertains 10 to make and use the same, reference being had to the accompanying drawings, which form a part of this specification.

My invention relates in general to car-trucks, and more particularly to trucks for 15 passenger-coaches.

It is customary at the present time to equip all first-class passenger-coaches with six-wheel trucks in order that there may be sufficient resiliency between the wheels and 20 the car-body to insure the comfort of passengers and at the same time sufficient structural strength to secure safety. Six-wheel trucks are, however, objectionable, in that they must necessarily have an extended 25 wheel-base, which when going around curves imposes great wear upon the flanges of the wheels, subjects the truck-frame to severe strain, and retards the movement of the car.

30 The primary object of my invention is to provide a four-wheel car-truck which will possess all of the advantages of a six-wheel truck without the disadvantages.

A further object of my invention is to provide a compact easy-riding car-truck which will neutralize the effects of shocks received by the wheels, due to rail-joints and other track irregularities.

40 A further object of my invention is to provide a car-truck having a short wheel-base, and consequently of short length, so that the center bearings may be located as near the ends of the car-body as possible, thereby preventing sagging of the car-body ends, due to 45 their own weight and to the friction of the buffing apparatus.

A still further object of my invention is to provide a car-truck which will be comparatively simple in construction, inexpensive in 50 manufacture, and efficient in use.

The embodiment of my invention herein disclosed may be generally described as a car-truck comprising two pairs of wheels, equalizing-bars on each side of the truck ex-

tending through the pedestals and resting on 55 the axle-bearings, vertical cylindrical springs supported upon the equalizing-bars intermediate of and outside of the pedestals upon which the side sills of the truck-frame rest, cross-sections parallel to the end sills and 60 rigidly connected at their ends to the side sills, longitudinal beams parallel to the side sills and rigidly connected at their ends to the cross-sections, suitable braces and tie-plates rigidly connecting the side and end 65 sills, the cross-sections, and longitudinal beams, spring-planks suspended by hangers from the end sills and cross-sections, two elliptical springs supported upon each spring- 70 plank, spring-bolsters supported upon the elliptical springs and located between the end sills and adjacent cross-sections, parallel longitudinal beams for supporting the center bearing formed integrally at their ends with the inner beams of the spring-bolsters, and 75 side bearings supported at their ends upon the ends of the spring-bolsters which project below and outside of the side sills.

My invention will be more fully described hereinafter with reference to the accompanying drawings, and in which—

Figure 1 is a plan view; Fig. 2, a side elevational view; Fig. 3, a sectional view on line 3 3, Fig. 1; Fig. 4, a view on line 4 4, Fig. 3; Fig. 5, an end elevation looking from the right in Fig. 1; Fig. 6, a sectional view on line 6 6, Fig. 1; and Fig. 7, a horizontal sectional view on line 7 7, Fig. 2, with the side and end sills of the truck-frame omitted.

The same reference characters are used to 90 designate the same parts in the several figures of the drawings.

Reference characters A' and A² designate pairs of wheels united by axles a' a². B' and B² designate the pedestals upon one side of 95 the truck-frame, and B³ and B⁵ the pedestals on the opposite side of the truck-frame. Located within the pedestals and surrounding the portions of the axles which extend therethrough are the usual brass journal-bearings a. 100

Located on each side of the truck outside of the wheels is an equalizer C, having portions C' and C² extending upwardly through the pedestals and resting upon the axle-bearings a. Each equalizer-bar after passing 105 through the pedestals projects downwardly and outwardly at its ends, as clearly shown in Fig. 2. The portions C' and C² of each

equalizer-bar which extend above the axles are provided with bars c' and c^2 , respectively, united thereto by bolts and extending below the axles. Supported upon each equalizer-bar are cylindrical springs E' , E^2 , E^3 , and E^4 , suitable caps e being secured to the equalizer-bar and forming seats for the lower ends of the springs. One of the cylindrical springs is located above each end of the equalizer-bar, while two of such springs are located intermediate of the pedestals. Supported upon the eight elliptical springs is a truck-frame composed of side sills D' and D^2 and end sills D^3 and D^4 , the side and end sills being rigidly united together in any suitable manner. The pedestals, which are of any usual construction, are secured to the side sills of the truck in a manner well known in the art. Caps E are interposed between the upper ends of the cylindrical springs and the lower surfaces of the side sills of the truck-frame.

In order to give the truck-frame sufficient rigidity, cross-sections P' and P^2 extend transversely between and are rigidly connected to the side sills and are spaced a sufficient distance away from the end sills, as shown in Fig. 3, to receive the truck-bolsters. The cross-sections are provided with vertical flanges p' and p^2 at their ends, which are rigidly secured to the inner vertical faces of the side sills. Bolts are shown as passing through the respective flanges p' and p^2 and also through the metallic plates and interposed wooden beam which compose the side sills. Each end of each cross-section is provided with a portion p , which extends over and rests upon the upper surface of the respective side sill. Interposed between the cross-sections P' and P^2 are longitudinal beams R' and R^2 , rigidly secured at their ends to the inner vertical surfaces of the cross-sections. Any suitable means may be provided for securing the ends of the beams R' and R^2 to the cross-sections—such, for instance, as plates r , which extend beneath and are riveted to the bottom flanges of the longitudinal beams and are provided with upturned flanges rigidly secured by means of bolts to the cross-sections.

Corner-plates T' and T^2 extend over and rigidly unite the end sill D^3 to the side sills and also to the cross-section P' . Such corner-plates are secured by vertical bolts to the end and side sills and are bent downwardly around the upper edge of the cross-section, as clearly shown in Figs. 3 and 4. Similar corner-plates T^3 and T^4 rigidly secure the end sill D^4 to the side sills and also to the cross-section P^2 . The corner-plates T' and T^2 are rigidly united by a brace t' , lying adjacent to the cross-section P' , while a similar brace t^2 rigidly connects the corner-plates T^3 and T^4 and lies adjacent the cross-section P^2 . The ends of the bases t' and t^2 are secured to the

ends of the longitudinal beams R' and R^2 and also serve to rigidly secure the respective corner-plates to the ends of the longitudinal beams, owing to rivets or other fastening device passing through the top flanges of the longitudinal beams, as shown in Fig. 3.

The side sills of the truck-frame are rigidly united intermediate of their ends by plates U' and U^2 , which overlie the top edges of the side sills and are bent downwardly to engage the inner faces thereof, as clearly shown in Fig. 6, and are also rigidly secured to the adjacent longitudinal beams R' and R^2 . The brace U' is provided with projections located in a slightly lower horizontal plane, to which are rigidly secured the ends of diagonal braces $u^2 u^2$, which diverge and are rigidly secured at their end to the beam R^2 and also to the corner-plates T^2 and T^4 . Similar diverging braces $u' u'$ rigidly connect the plate U^2 with the ends of the beam R' and also with the corner-plates T^2 and T^3 . Additional transverse braces, such as U^3 and U^4 , may also be provided for rigidly connecting the longitudinal beams R' and R^2 , such braces being also rigidly connected to the pairs of diverging braces u' and u^2 , over which they pass.

Located beneath and pivotally supported by the end sill D^4 are hangers $F' F^2$, the upper ends of said hangers being bifurcated, as shown in Fig. 2, and extending on opposite sides of yokes $f' f^2$. Such yokes pass vertically through the end sill D^4 and are provided with retaining-nuts on their upper ends, as shown in Fig. 5. Bolts f are carried at the upper bifurcated ends of the hangers $F' F^2$ and pass through the yokes $f' f^2$, thereby pivotally connecting the hangers to the end sill. Hangers F^3 and F^4 , located in longitudinal alignment with the hangers $F' F^2$, are pivotally connected at their upper ends by pins f^3 and f^4 to the cross-section P^2 adjacent its ends. Hanger-axles K' and K^2 are carried by the lower ends of the hangers F' and F^2 and F^4 , respectively, and upon such hanger-axles is supported a spring-plank G^2 . The spring-plank G^2 may conveniently consist in a channel-beam, the flange of which extends downwardly. A filler-block g^2 is interposed between the hanger-axles and the spring-plank, as shown in Fig. 2.

A spring-plank G' , similar to spring-plank G^2 , is supported at the opposite end of the truck upon hanger-axles K' and K^2 , the latter being supported at their opposite ends in pairs of hangers similar to those above described—that is, hangers F' and F^2 depend from the end sill D^2 and other hangers F^3 and F^4 depend from the cross-section P' . Filler-blocks g' are interposed between the downward-extending flanges of the spring-plank G' and the underlying hanger-axles. Supported upon the spring-plank G' are two sets of elliptical springs $H' H^2$, while similar sets of elliptical

5 springs H^3 and H^4 are supported upon the spring-plank G^2 . Supported by the sets of elliptical springs H' H^2 is one truck-bolster, which lies between the end sill D^2 and cross-section P' , while a similar bolster is support-
10 ed upon the sets of elliptical springs H^3 and H^4 and lies between the end sill D^4 and the cross-section P^2 . Each of the bolsters comprises a transverse I-beam L' , to which are rigidly secured bent I-beams L^2 . Each of such I-beams is bent so as to extend parallel with each of the beams L' and to extend longitudinally between such beams, as shown in Fig. 7. The longitudinal portions l^2 of the
15 I-beams L^2 are rigidly connected together by an interposed I-beam l , the flanges of which are riveted to the webs of the I-beams, as clearly shown in Figs. 6 and 7. Rigidly connected to the webs of the longitudinal portions l^2 of the bent I-beams L^2 are plates o^2 o^2 , which terminate at their ends flush with the web of the outwardly-bent portions of the beams L^2 . The opposite ends of the plates o^2 o^2 are united by integrally-thickened portions O' and O^2 , which are rigidly secured to transverse plates N' and N^2 . The plates N' and N^2 are rigidly secured to the webs of the transversely-extending portions of the beams L^2 and are thickened at their centers. Bolts
20 o^3 , provided with spreading sleeves, tie together the I-beam L' , the plate N' , and the end O' of the tie-plates o^2 . Similar bolts o^4 , provided with spreading sleeves, rigidly unite the I-beam forming part of the opposite bolster with the transverse plate N^2 and the thickened end O^2 of the longitudinal tie-
25 plates o^2 .

In order that each transverse beam L' may be rigidly united to the parallel portions of the I-beams L^2 , braces, such as shown in Figs. 3 and 7, are employed. Each of such braces consists in an inclined plate L^3 , united at its opposite ends to the webs of the I-beams L' L^2 , the end which is united to the web of the beam L^2 being also united to the interposed transverse plate N' or N^2 . Supplemental braces l^3 and l^4 extend from near the center of the brace L^3 on opposite sides thereof and are united at their ends to the webs of the I-beams L' and L^2 .

In order to assume the wear incident to the vertical movement of the bolsters relatively to the end sills and adjacent cross-sections, chafing-plates are provided. In Fig. 3, s^3 indicates one of such plates secured to the inner surface of the end sill D^2 , which co-operates with a filler-block S^3 , secured to the outer surface of the I-beams L' , while a similar filler-block S' is secured to the outer surface
55 of the I-beam L^2 and co-operates with a plate s' , secured to the cross-section P' and having a horizontal lower portion which extends beneath the end of the longitudinal beam R' and is secured thereto through the medium
60 of a filler-block R . By reference to Fig. 7 it

will be seen that two sets of chafing-plates are provided between the cross-section P' and the portion of the adjacent bolster which consists in the outwardly-projecting ends of the channel-beams L^2 and that similar coöperating chafing-plates s^2 and S^2 are interposed between the cross-section P^2 and the adjacent portion of the bolster. The chafing-
70 plates between the end sills and the I-beams L' of the bolsters are located in alinement 75 with the chafing-plates between the cross-sections and the bolsters.

The ends of the bolsters are cut away at their tops and project beneath and beyond the side sills to afford supports for side bearings M' and M^2 . The side bearing M' is provided at its ends with flattened portions which are rigidly secured to the projecting ends of the bolsters and is provided with a side bearing-plate M in transverse alinement 85 with a center bearing-plate O , rigidly secured to the longitudinal portions of the beams L^2 . The side bearing M^2 is provided with flattened end portions m^2 , which are rigidly secured to the ends of the bolsters which project at the 90 opposite side of the truck and is also provided with a bearing-plate M . To increase the strength of the reduced ends of the bolsters upon which the side bearings are supported, reinforcing-plates l^7 and l^8 are secured to the outer surfaces of the ends of the beams L' and L^2 . The I-beam L' of each bolster is secured to the adjacent portions of the I-beams L^2 by plates L^5 and L^6 , respectively, extending across and secured to the 95 tops of the beams, and by similar plates l^5 and l^6 , extending across and secured to bottom flanges of the beams.

Pedestal-straps b' b^2 extend across the openings in the bottoms of the pedestal B' 105 and B^2 and are preferably formed integrally with a rod c , such rod being extended around the portions of the equalizer-bar C at each side of the pedestal and at its opposite ends bent upwardly and are secured to the side 110 sill D' , as clearly shown in Fig. 2. Similar pedestal-straps extend beneath the pedestals B^3 and B^4 at the opposite side of the truck and are formed integrally with a tie-rod c , the ends of which are bent upwardly and are 115 secured beneath the side sill D^2 . The tie-
120 rods c are united by transverse strips C^3 and C^4 at their opposite ends adjacent to their vertically-extending portions, as clearly shown in Figs. 2 and 6.

From the foregoing description it will be observed that I have invented an improved car-truck comprising four wheels, the two at each side of the truck being located near together, and thereby constituting a short 125 wheel-base, so as to permit the truck to freely travel around curves, which, owing to the cylindrical and elliptical springs, supports the car-body with sufficient elasticity to dissipate any shocks received by the 130

wheels and which is so constructed as to possess great structural strength.

While I have described more or less precisely the details of construction, I do not wish to be understood as limiting myself thereto, as I contemplate changes in form, the proportion of parts, and the substitution of equivalents, as circumstances may suggest or render expedient, without departing from the spirit of my invention.

Having now fully described my invention, what I claim as new, and desire to secure by Letters Patent, is—

1. In a car-truck the combination with a pair of axles and wheels thereon, of equalizer-bars on the outside of each pair of wheels, springs mounted upon the equalizer-bars, a truck-frame supported upon said springs, spring-planks depending from the opposite ends of the truck-frame, springs mounted upon said planks, bolsters supported upon said springs, longitudinal beams rigidly connecting the bolsters at each end of the truck, and a central bearing supported upon said longitudinal beams.

2. In a car-truck the combination with a truck-frame, of equalizer-bars beneath the side sills of the truck-frame and extending over the axle journal-bearings, coiled springs interposed between the equalizer-bars and side sills of the truck-frame, spring-planks depending from the opposite ends of the truck-frame, elliptical springs mounted upon said planks, bolsters supported upon said elliptical springs, and longitudinal beams rigidly connecting the bolsters at each end of the truck.

3. In a car-truck, the combination with two axles having wheels thereon, of a truck-frame, equalizer-bars located beneath the side sills of the truck-frame and extending above the axle journal-bearings, coiled springs mounted upon the equalizer-bars at the ends thereof and intermediate of the axles upon which the side sills of the truck-frame are supported, spring-planks depending from the opposite ends of the truck-frame, two elliptical springs supported upon each plank, a bolster supported upon the pair of elliptical springs above each plank, and longitudinal beams rigidly connecting the bolsters at each end of the truck.

4. In a car-truck, the combination with axles and wheels thereon of a truck-frame, equalizer-bars located beneath the side sills of the truck-frame and extending around the axle journal-bearings, coiled springs interposed between the equalizer-bars and side sills of the frame, spring-planks depending from the opposite ends of the truck-frame, elliptical springs mounted upon said planks, bolsters supported upon said elliptical springs the ends of which project beneath and outside of the side sills of the frame, side bearings the ends of which are supported upon

the projecting ends of the bolsters, and longitudinal beams rigidly connecting the bolsters at the opposite ends of the truck.

5. In a car-truck, the combination with the axles and wheels thereon, of a truck-frame, equalizer-bars located beneath the side sills of the frame and supported upon the axle journal-bearings, coiled springs interposed between the equalizer-bars and side sills of the truck, cross-sections rigidly uniting the side sills adjacent to but spaced apart from the end sills of the truck-frame, spring-planks depending from the end sills and adjacent cross-sections, springs mounted upon said planks, bolsters located between each end sill and the adjacent cross-section and supported above said spring-plank, and longitudinal beams for rigidly connecting the bolsters at the opposite ends of the truck.

6. In a car-truck, the combination with the axles and wheels thereon of a truck-frame, equalizer-bars located beneath the side sills of the frame and supported upon the axle journal-bearings, coiled springs interposed between the equalizer-bars and side sills of the truck, cross-sections rigidly uniting the side sills adjacent to but spaced apart from the end sills of the truck-frame, spring-planks depending from the end sills and adjacent cross-sections, springs mounted upon said planks, bolsters located between each end sill and the adjacent cross-section and supported above said spring-plank, longitudinal beams for rigidly connecting the bolsters at the opposite ends of the truck and chafing-plates interposed between the opposite surfaces of the bolsters and the adjacent surfaces of the end sills and cross-sections.

7. In a car-truck, the combination with the axles and wheels thereon of a truck-frame, equalizer-bars located beneath the side sills of the frame and supported upon the axle journal-bearings, coiled springs interposed between the equalizer-bars and side sills of the truck, cross-sections rigidly uniting the side sills adjacent to but spaced apart from the end sills of the truck-frame, spring-planks depending from the end sills and adjacent cross-sections, springs mounted upon said planks, bolsters located between each end sill and the adjacent cross-section and supported above said spring-plank, and longitudinal beams for rigidly connecting the bolsters at the opposite ends of the truck, longitudinal beams rigidly connected at their ends to the cross-sections and corner-braces rigidly uniting the end and side sills to the cross-sections and longitudinal beams.

8. In a car-truck, the combination with the axles and wheels thereon of a truck-frame, equalizer-bars located beneath the side sills of the frame and supported upon the axle journal-bearings, coiled springs interposed between the equalizer-bars and side sills of the truck, cross-sections rigidly unit-

ing the side sills adjacent to but spaced apart from the side sills of the truck-frame, spring-planks depending from the end sills and adjacent cross-sections, springs mounted upon 5 said planks, bolsters located between each end sill and the adjacent cross-section and supported above said spring-planks, longitudinal beams for rigidly connecting the bolsters at the opposite ends of the truck, longitudinal beams rigidly connected at their ends 10 to the cross-sections and corner-braces rigidly uniting the end and side sills to the cross-sections and longitudinal beams, intermediate braces rigidly uniting the side sills to said longitudinal beams and diagonal braces uniting 15 said corner and intermediate braces.

9. In a car-truck, the combination with a pair of axles and wheels thereon, of a truck-frame, equalizer-bars supported upon the axle 20 journal-bearings, coiled springs interposed between the equalizer-bars and side sills of the truck-frame, spring-planks depending from the opposite ends of the truck-frame, springs mounted upon said planks, bolsters supported 25 upon said spring-planks each composed of an I-beam connected to adjacent parallel end portions of two longitudinal I-beams extending between and rigidly connecting the bolsters.

30 10. In a car-truck, the combination with a pair of axles and wheels thereon, of a truck-frame, equalizer-bars supported upon the axle journal-bearings, coiled springs interposed between the equalizer-bars and side sills of 35 the truck-frame, spring-planks depending from the opposite ends of the truck-frame, elliptical springs mounted upon said planks, a structure supported upon said elliptical springs composed of transverse I-beams located adjacent the end sills of the truck and 40 central parallel longitudinal I-beams extending between said transverse I-beams and having outwardly-bent portions located adjacent and rigidly secured to said transverse I-beams, and a center bearing supported upon 45 said longitudinal central I-beam.

11. In a car-truck, the combination with a pair of axles and wheels thereon, of a truck-frame, equalizer-bars supported upon the axle 50 journal-bearings, coiled springs interposed between the equalizer-bars and side sills of the truck-frame, spring-planks depending from the opposite ends of the truck-frame, elliptical springs mounted upon said planks, 55 a structure supported upon said elliptical springs composed of transverse I-beams lo-

cated adjacent the end sills of the truck and central parallel longitudinal I-beams extending between said transverse I-beams and having outwardly-bent portions located adjacent and rigidly secured to said transverse I-beams, 60 a center bearing supported upon said longitudinal central I-beam, a strengthening I-beam interposed between and rigidly secured to the longitudinal portions of said central I-beams and transverse plates located parallel to said transverse I-beams and rigidly uniting the oppositely-extending end portions of said central I-beams.

12. In a car-truck, the combination with a pair of axles and wheels thereon, of a truck-frame, equalizer-bars supported upon the axle journal-bearings, coiled springs interposed between the equalizer-bars and side sills of the truck-frame, spring-planks depending from the opposite ends of the truck-frame, 75 elliptical springs mounted upon said planks, a structure supported upon said elliptical springs composed of transverse I-beams located adjacent the end sills of the truck and central parallel longitudinal I-beams extending 80 between said transverse I-beams and having outwardly-bent portions located adjacent and rigidly secured to said transverse I-beams, a center bearing supported upon said longitudinal central I-beams, 85 a strengthening I-beam interposed between and rigidly secured to the longitudinal portions of said central I-beam, transverse plates located parallel to said transverse I-beams and rigidly uniting the oppositely-extending end portions of said central I-beams, the ends of said transverse I-beams and the adjacent portions of the central I-beams being reduced and extending beneath the side sills of the truck-frame, and 90 side bearings supported upon the projecting ends of said transverse I-beams.

13. In a car-truck the combination with a pair of axles and wheels thereon, of equalizer-bars at the sides of the truck, springs mounted upon said equalizer-bars, a truck-frame supported upon said springs, spring-planks supported by the ends of the truck-frame, 100 springs carried by said planks, bolsters supported by said springs, and means rigidly connecting the bolsters at the ends of the truck.

In testimony whereof I sign this specification in the presence of two witnesses.

PETER N. HYDEN.
